UNITED STATES PATENT OFFICE.

LYMAN B. CUTLER, OF MONMOUTH, ASSIGNOR OF ONE-HALF TO WALLACE GREENE, OF FREEPORT, ILLINOIS.

BAG-LOCK.

SPECIFICATION forming part of Letters Patent No. 396,029, dated January 8, 1889.

Application filed December 1, 1888. Serial No. 292,415. (No model.)

To all whom it may concern:

Be it known that I, LYMAN B. CUTLER, a resident of Monmouth, in the county of Warren and State of Illinois, have invented certain new and useful Improvements in Mail-Bags; and I do hereby declare the following to be a full, clear, and exact description of the invention, such as will enable others skilled in the art to which it pertains to make and use the same.

My invention relates to improvements in mail-bag locks, and is fully described and claimed in this specification, and shown in the accompanying drawings, wherein—

15 Figure 1 shows the upper part of an open bag provided with my devices. Fig. 2 is a partial top view of the same when closed, a small portion being shown in section. Fig. 3 is a section on the line $x-x$, Fig. 2. Fig. 4 is 20 a side view of the parts seen in Fig. 2.

The object of the invention is to provide a mail-bag that by the simple act of closing it shall be secured at a series of points in such manner that locking with an ordinary padlock may prevent disengagement at any of 25 the said points.

To accomplish the objects an ordinary bag, A, is provided at its open end with two opposing metallic jaws, B B', bent downward at 30 each end and pivoted together at C, so that when open they form an approximately-rectangular frame. The jaws may be conveniently formed of two strips, B'' B''', the inner one flat, the outer L-shaped in cross-section, 35 and between these the edges of the mail-bag are secured by rivets D. The inner face of one of the jaws bears a series of hooked projections, E, and the inner face of the other a series of correspondingly-arranged catches, 40 E', adapted to receive the hooks E when the jaws are closed. In order that they may engage, however, the jaws must move longitudinally with reference to each other and then return to their normal position, bringing the 45 jaws within the catches. To cause this movement automatically as the jaws close, lugs G G' are so placed upon the jaws, respectively, that as the mail-bag closes the end of one lug passes along the inclined surface of 50 a projection on the other, forcing them in opposite directions far enough to let the hooks pass the ends of the catches. Just as this

point is reached a change in direction of the impinging surfaces of the lugs permits the return movement of the jaws, and all the 55 hooks engage simultaneously. Evidently they can be disengaged only by again moving the jaws bodily with reference to each other, and if this be prevented the mail-bag is secured at as many points as there are 60 hooks. The jaws are thus secured by passing the link of a lock through the two jaws or any fixed attachments thereof.

It is evident that there may be great variation in construction while keeping within 65 the scope of my invention, and I do not therefore wish to limit myself to the precise construction shown; but to illustrate the invention I have shown the hooks as all upon one jaw and the catches as staples and all upon 70 the opposite jaw, the lugs as provided, respectively, with a V-shaped projection, H, and a depression adapted to receive that projection, the lock I as passed through the two lugs that serve to offset the jaws to permit 75 engagement of the hooks, and the jaws themselves of light sheet metal closely riveted at C, the elasticity of the downwardly-bent portions being relied upon to permit the necessary offset of the jaws and also to return 80 them to their normal positions when the hooks are in position for engagement; but it is quite immaterial to the more important principles of my invention whether all these details be followed.

85

What I claim is—

1. In a mail-bag, the combination, with two pivotally-connected opposing jaws secured to the edges of the bag's open end, of a series of hooks arranged at intervals along the inner face of one of said jaws, a series of catches arranged at corresponding intervals along the inner face of the opposing jaw, and lugs having inclined impinging surfaces fixed upon the respective jaws and overlapping when the 95 jaws are closed, whereby the jaws may be thrown bodily in opposite directions as the bag closes to permit engagement of the hooks, substantially as set forth.

2. The combination, with a mail-bag, of two opposing jaws secured to the bag's edges, a series of rigid hooks arranged at intervals along one of said jaws, a series of catches placed at corresponding intervals along the

other jaw and adapted to be simultaneously engaged by said hooks when the jaws are moved bodily in the proper direction with reference to each other, and the lock passing through both jaws, or projections thereon, to prevent such bodily motion.

3. The combination, with a mail-bag, of the downwardly-bent pivotally-connected jaws secured to its edges, the staples fixed at intervals upon one of said jaws, the correspondingly-placed hooks fixed upon the opposing face of the other jaw and adapted to engage the staples respectively, the lug fixed upon one jaw and having the V-shaped projection,

the overlapping lug fixed upon the opposing jaw and provided with a corresponding depression, and the lock having its link passed through both lugs and preventing bodily movement of the jaws with reference to each other, substantially as set forth.

In testimony whereof I have signed this specification in the presence of two subscribing witnesses.

LYMAN B. CUTLER.
